ANCHOR FOR CYLINDER BORING MACHINES

Filed Dec. 8, 1947

UNITED STATES PATENT OFFICE

2,502,983

ANCHOR FOR CYLINDER-BORING
MACHINESOlov J. E. Olsson, Minneapolis, Minn., assignor to
Storm Vulcan Company, Inc., Minneapolis,
Minn., a corporation of Minnesota

Application December 8, 1947, Serial No. 790,270

2 Claims. (Cl. 77—2)

1

This invention has relation to an anchor for cylinder boring machines.

An object of the invention is to provide an anchor of novel and improved construction for fastening a cylinder boring machine upon an engine block having cylinders to be bored in fixed relation to the block and cylinders.

A further object is to provide an anchor for fastening a cylinder boring machine upon an engine block having cylinders to be bored in fixed relation to the block and cylinders which will include desirable, new and improved features and characteristics of construction.

And a further object is to provide a cylinder boring machine anchoring device incorporating features and characteristics as hereinafter set forth.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible as long as within the spirit of the invention and the scope of the claims which follow.

In the accompanying drawings forming a part of this specification,

Fig. 1 is a side elevational view of an anchor made according to the invention, the view also disclosing, in section, a cylinder of an engine block in which the anchor is situated, and, in elevation, a fragment of the base of a cylinder boring machine with which said anchor is assembled;

Fig. 2 is a top plan view of the anchor of Fig. 1, partially broken away and partially in section;

Fig. 3 is an end elevational view of the anchor as it would appear from the left in Figs. 1 and 2 with an adapter of said anchor removed, the disclosure of Fig. 3, however, including a clamping member of reduced size and length;

Fig. 4 is a longitudinal sectional view of the disclosure of Fig. 3, taken as on line 4—4 in Fig. 5; and

Fig. 5 is a longitudinal sectional view of said disclosure of Fig. 3, taken as on line 5—5 in Fig. 4, the disclosure of Fig. 5, however, including an anchoring pin of length less than that of the anchoring pin shown in Figs. 1 and 2.

With respect to the drawings and the numerals of reference thereon, 10 denotes the base of

2

a cylinder boring machine having a boring tool (not shown) adapted to be operative upon cylinders to be rebored of a cylinder block 11. As disclosed, the cylinder boring machine base 10 is supported on the cylinder block 11, and the anchor of the invention is for removably securing said cylinder boring machine to said cylinder block at a cylinder 12 of the block other than a cylinder to be rebored, according to practice which is usual, the cylinder block 11 of course including cylinders, not necessary to be shown, additional to the cylinder 12.

The cylinder boring machine base 10 includes spaced apart upright walls but one of which, indicated 13, is shown, and each upright wall 13 includes an inwardly extending shelf but one of which, designated 14, is disclosed. The shelves will be situated in spaced, parallel relation to each other adjacent the lower end portions of the upright walls of the base 10.

The new and improved anchor is adapted to be situated within a cylinder, such as 12, of a cylinder block, such as 11, adjacent a cylinder to be rebored, and a connector 15 constituting an upper unit of said anchor is for interconnecting the anchor with the cylinder boring machine base 10, or with a clamp (not shown) assembled with said cylinder boring machine base and including inwardly extending shelves such as 14.

An intermediate unit of the anchor includes a block of metal, or other rigid material, providing a hollow elongated body 16 integrally supporting a laterally projecting element 17 at a side of its upper end portion, a transverse wall 18 adjacent said laterally projecting element and aligned with said hollow elongated body, and spaced apart, parallel legs 19, 19 situated at the lower end of the hollow elongated body in spaced relation to the transverse wall and the laterally projecting element and in vertical alignment with said hollow elongated body and said transverse wall. An anchoring pin 20, slidably situated in a transverse opening 21 in the laterally projecting element 17 at the side of said laterally projecting element opposite the transverse wall 18, includes a beveled inner end 22 and a rounded outer end 23. A stop pin 24, in the transverse opening 21 adjacent the hollow elongated body 16, is for limiting the extent of inward movement of the anchoring pin 20, and a set screw 25 is for retaining a spring pressed ball 26 in engagement with said anchoring pin to cause the anchoring pin to be frictionally slidably retained in said transverse opening. A fixing screw 27 in a threaded opening 28 in the upper end of the laterally pro-

jecting element 17, adjacent the transverse wall 18 and perpendicular to the anchoring pin 20, is adapted to be turned down against the beveled inner end 22 of said anchoring pin to cause the anchoring pin to be forcibly moved outwardly of the transverse opening 21.

The hollow elongated body 16 is of generally rectilinear configuration and is adapted to detachably support an adapter 29 situated between the transverse wall 18 and the spaced apart, parallel legs 19, 19 at the side of said hollow elongated body opposite the laterally projecting element 17 substantially in alignment with said laterally projecting element and the anchoring pin 20 in direction transversely of the hollow elongated body.

The adapter 29 is constituted as a flat, elongated base member 30 integrally supporting spaced apart, parallel, relatively narrow extension pieces 31, 31 at one of its sides and spaced apart, parallel, comparatively wider extension pieces 32, 32 at its opposite side. The extension pieces 31, 32 and 31, 32 are in aligned relation in direction thicknesswise of the flat, elongated base member 30, and the extension pieces 31, 31 and 32, 32, respectively, are spaced apart a distance substantially equal to, or a trifle greater than, a measurement representing the thickness of the hollow elongated body 16. The extension pieces are in perpendicular relation to the flat, elongated base member 30 as shown, and the free side edges of all of said extension pieces include arcuate surfaces 33.

The flat, elongated base member 30 of said adapter 29 includes an opening 34 for removably receiving an attaching screw bolt 35 adapted to be turned home in a threaded opening 36 in an adjacent wall of the hollow elongated body 16 to cause the adapter to be detachably secured to and upon said hollow elongated body, and said flat, elongated base member 30 can be fastened up against the adjacent surface of the hollow elongated body either with the spaced apart, parallel elements 31, 31 in overlapping relation to said hollow elongated body and the spaced apart, parallel elements 32, 32 projecting outwardly, or with said spaced apart, parallel elements 32, 32 in overlapping relation to the hollow elongated body and said spaced apart, parallel elements 31, 31 projecting outwardly. When the elements 31, 31 are in overlapping relation to the hollow elongated body the elements 32, 32 are adapted to function as extension pieces, and vice versa.

The construction and arrangement and the overall dimension in horizontal direction of the intermediate unit of the anchor, including the adapter 29 and the block of metal, or other rigid material, providing the hollow elongated body 16 and the laterally projecting element 17, will be such that the fixing screw 27 can be turned down against the beveled inner end 22 of the anchoring pin 20 to cause the arcuate surfaces 33 of the extension pieces, 31, 31 or 32, 32, as the case may be, and the rounded outer end 23 of said anchoring pin to be pressingly engaged against diametrically opposite portions of the internal cylindrical surface of a cylinder such as 12, about as disclosed in Fig. 1 of the drawings, thus to cause said intermediate unit of the anchor to be grasped within the cylinder against the possibility of accidental displacement.

It will be evident that when the adapter 29 is placed upon the elongated body 16 with the relatively narrow pieces 31, 31 in overlapping rela-

tion to said hollow elongated body so that the comparatively wider elements 32, 32 can serve as extension pieces, the anchor will be adapted to span a cylinder of greater diameter than when said adapter is placed upon said hollow elongated body with the comparatively wider pieces 32, 32 in overlapping relation to the hollow elongated body so that the relatively narrow elements 31, 31 can serve as extension pieces. Stated otherwise, the adapter 29 constitutes an entity of the intermediate unit of the anchor which can be employed selectively to cause the overall dimension in horizontal direction of said intermediate unit to be increased to render said anchor capable of being grasped within cylinders of larger diameter and to cause the overall dimension in horizontal direction of the intermediate unit to be decreased to render the anchor capable of being grasped within cylinders of smaller diameter. And by employment of an anchoring pin such as 20 of suitable length, in connection with an intermediate unit employing an adapter such as 29 having extension pieces such as 31, 31 or 32, 32 of suitable width, an anchor made according to the invention can be grasped in a cylinder of any of several different diameters. The principle incorporated in the anchor of the present invention is such that an intermediate unit of said anchor, by utilizing adapters such as 29 with extension elements such as 31, 31 and 32, 32 of varying widths and anchoring pins such as 20 of varying lengths, can be rendered capable of being grasped in cylinders which vary considerably in diameter, as will be apparent.

A lower unit of the anchor is constituted as an elongated bar 37 of metal, or other rigid material, having its midlength situated between and pivotally supported, as at 38, upon lower end portions of the spaced apart, parallel legs 19, 19. The elongated bar 37 comprises a clamping member of the anchor. It includes upwardly facing surfaces 39, 39 upon its opposite end portions adapted to be engaged beneath and against oppositely disposed, lower surfaces of a cylinder block adjacent the lower end of a cylinder such as 12 in which said anchor is situated, as will be apparent from Figs. 1 and 2 of the drawings. Said elongated bar 37 is supported upon the spaced apart legs 19, 19 for swinging movement in a vertical plane. The construction and arrangement will be such that said elongated bar 37 can be swung to acute angle relation to the intermediate unit of the anchor and passed downwardly through a cylinder, and the elongated bar can be swung while beneath the cylinder to substantially right angular relation to said intermediate unit. Or, in any instance when preferable, the intermediate unit of the anchor can be passed upwardly into a cylinder. It will be apparent that longer clamping members, as in Figs. 1 and 2, will be suitable for use with cylinders of larger diameter, and shorter clamping members, as in Figs. 3, 4 and 5, will be suitable for use with cylinders of smaller diameter.

Attention is called to the fact that the anchor which the invention presents need not necessarily be situated centrally of a cylinder such as 12. While the intermediate unit of said anchor will span the diameter of a cylinder in which the anchor is grasped, the lower unit, or clamping member constituted as the elongated bar 37, can be situated at variable distances from the side surface of the cylinder, closer to or farther from said side surface, as may suit convenience.

Stated otherwise, a clamping member or elongated bar, such as 37, of the anchor need not be situated diametrically across a cylinder containing said anchor. Instead, the lower unit of the anchor can be situated at any location, found suitable in some instance or other, between a location where said lower unit is closely adjacent the side wall of a cylinder and a location where the lower unit extends diametrically across a cylinder.

The connector 15 is constituted as a vertical retaining screw 40 situated in an internal thread 41 of the transverse wall 18 of the intermediate unit of the anchor and having a horizontal annular flange or head 42 upon its upper end. An upper portion of the vertical retaining screw 40, beneath the horizontal annular flange or head 42, is adapted to lie in the space between the inwardly extending shelves on the upright walls of the base 10, and portions of the lower surface of said horizontal annular flange or head 42 are adapted to be engaged against portions of the upper surfaces of said inwardly extending shelves. The lower end portion of the vertical retaining screw 40 is situated in the hollow elongated body 16 beneath the transverse wall 18 and above the lower unit of the anchor.

Evidently, the anchor will be readily and easily removable from a cylinder upon release of the anchoring pin 20 by partial withdrawal of the fixing screw 27.

What is claimed is:

1. In an anchor for fastening a machine base upon and against a block including a cylinder,

5 a unit adapted to be situated within said cylinder in grasping relation to an internal cylindrical surface thereof, comprising a body member, an anchoring element situated in said body member at a side thereof, means for causing said anchoring element to be forcibly moved outwardly of said body member, and an adapter constituted as a base member supporting spaced apart, relatively narrow extension pieces at one of its sides 10 and spaced apart, comparatively wider extension pieces at its opposite side adapted selectively to be situated in overlapping relation to portions of said body member detachably supported on the body member at a side thereof opposite said 15 anchoring element substantially in alignment with the anchoring element.

2. The combination as specified in claim 1 wherein said means is constituted as a fixing screw in the body member adapted to be turned down against said anchoring element.
